(57) **CLAIM**

The ornamental design for a handle for a dental instrument, as shown and described.

DESCRIPTION

FIG. 1 is an isometric view of a handle for a dental instrument exemplary of a first aspect of the present inventive design; FIG. 2 is a left side elevational view of the handle of FIG. 1; FIG. 3 is a front elevational view of the handle of FIG. 1; FIG. 4 is a right side elevational view of the handle of FIG. 1; FIG. 5 is a back elevational view of the handle of FIG. 1; FIG. 6 is a top end plan view of the handle of FIG. 1; FIG. 7 is a bottom end plan view of the handle of FIG. 1; FIG. 8 is an isometric view of a handle for a dental instrument exemplary of a second aspect of the present inventive design; FIG. 9 is a left side elevational view of the handle of FIG. 8; FIG. 10 is a front elevational view of the handle of FIG. 8; FIG. 11 is a right side elevational view of the handle of FIG. 8;

FIG. 12 is a back elevational view of the handle of FIG. 8; FIG. 13 is a top end plan view of the handle of FIG. 8; and, FIG. 14 is a bottom end plan view of the handle of FIG. 8. Broken lines in the drawings are for the purposes of illustrating environmental structure and form no part of the claimed designs.

1 Claim, 8 Drawing Sheets
